UNITED STATES PATENT OFFICE.

RUFUS KING, OF PLAINVILLE, MASSACHUSETTS, ASSIGNOR TO BUGBEE & NILES COMPANY, OF NORTH ATTLEBORO, MASSACHUSETTS.

BUCKLE OR CLASP.

Application filed August 1, 1924. Serial No. 729,508.

To all whom it may concern:

Be it known that I, RUFUS KING, of Plainville, a citizen of the United States, residing at Plainville, in the county of Norfolk and State of Massachusetts, have invented new and useful Improvements in Buckles or Clasps, of which the following is a specification.

This invention relates to certain new and useful improvements in buckles or clasps and pertains more particularly to the ribbon holding bar and the manner of connecting same to the buckle or clasp.

The primary object of the invention is to provide a bar which can be applied to the buckle or clasp without bending of parts of the buckle or clasp.

A still further object of the invention is to provide a bar which can be easily and quickly applied to and removed from the buckle or clasp, and more specifically to provide a bar which is expansible and contractible, whereby upon contraction the bar may be positioned in the buckle or clasp and upon release will automatically expand and be operatively related to the buckle or clasp.

A still further object of the invention is to provide simple and economical means for the above purpose.

The invention has still further and other objects, which will be later set forth and manifested in the course of the following description.

The invention is particularly adapted to and related to ribbon bracelets.

In the drawings:—

Figure 1, is a plan view of the invention applied to a buckle, the ribbon being broken away and shown partly in section;

Figure 2 is a section on line 2—2 of Figure 1;

Figure 3 is a section on line 3—3 of Figure 2;

Figure 4 is a view similar to Figure 1 showing a modified form of the invention applied to the female member of a clasp;

Figure 5 is a section on line 5—5 of Figure 4, and

Figure 6 is a section on line 6—6 of Fig. 5.

It will be understood that either form of the invention is applicable to a buckle or clasp. In the preferred form of Figs. 1—3, the bar A embodies a sleeve 1 having an interior shoulder 2 adjacent its outer end, 55 on which shoulder a seat forming disk 3 is

engaged. A rod-like member 4 has its inner end slidable in the sleeve 1 and is reduced at 5 forming a head 6 between which latter and the disk 3 a coil spring 7' is arranged. A teat 7 is struck-out from the sleeve 1 and engages in the reduced part 5 to thereby restrict outward movement of the rod 4 under the tension of the spring 7'. A short sleeve 8 is shouldered on its interior and engages over the outer end of the rod 4 and to which latter it may be secured in any suitable manner.

In use of the invention with a buckle, the tongue T thereof is engaged over the rod 4 and is held in place by the ribbon strap R, 70 the latter as usual being slotted to receive the tongue. The pintles P of the buckle are received in the sockets at the bar ends, one of the sockets being formed by the sleeve 8 and the other by the open outer end of the 75 sleeve 1 beyond the disk 3. It will thus be apparent that by relative approaching or contractible movement of the rod 4 and sleeve 1, the length of the bar is reduced, and whereupon the sockets at the ends thereof may be aligned with the pintles P and upon release of the parts the spring 7' will move the parts to the position of Figs. 1 and 2 wherein the pintles are socketed in the bar ends.

In the modified form of the invention the bar B is composed of a central rod 10, each end of which has a cut-out portion 11 providing end shoulders. A sleeve 12 is slidably mounted on each end of the rod and has a struck out teat 13 engaging in adjacent cut-out 11 and with the shoulders at the ends of the same.

A central coil spring 14 surrounds the rod and bears at its ends against the inner 95 ends of the sleeves. The clasp C has pintles P' corresponding to the pintles P of the buckle, the operation being the same as in the instance of the buckle.

Having thus described my invention; 100 what I claim as new and desire to secure by Letters Patent is:—

1. In a securing device for ribbons, a body having confronting pintles, a sectional bar having sockets at its ends to receive the pintles, and means to tension the sections and to permit of relative expansible and contractible movement thereof, so as to enable the pintles to be released from the bar sockets upon contraction of the sections. 110

2. In a securing device for ribbons, a body having confronting pintles, a bar having sockets to receive the pintles and means to permit approaching and receding movement of the sockets to allow the bar to be applied to the body with the sockets receiving the pintles.

3. In combination with a body having confronting pintles, a rod having a sleeve 10 on one end thereof forming a socket to receive one of the pintles, a socket at the opposite end of the rod to receive the other pintle, and a spring on the rod to tension one of the sockets and to permit same to 15 approach the other socket.

4. In combination with a body having confronting pintles, a rod, a sleeve-forming socket on one end of the rod, a slidable sleeve-forming socket on the opposite end of 20 the rod, means to limit sliding of the second sleeve on the rod and a coil spring interposed between an end of the rod and the second sleeve to tension the latter.

5. In combination with a body having

confronting pintles, a rod, a sleeve-forming 25 socket on each end of the rod to receive the respective pintles, means to restrict sliding movement of each of the sleeves, and a coil spring on the rod interposed between the sleeves to tension each thereof.

6. In combination with a body having confronting pintles, a ribbon engaging bar having socketed ends to receive the pintles, spring means associated with the bar, one of the socketed ends being movable relative 35 to the bar and against the tension of said spring means to allow said movable socketed end to be moved to receive one of the pintles when the other pintle is placed in the socket at the other end of the bar.

In testimony whereof I have signed my name to this specification in the presence of 40 two subscribing witnesses.

RUFUS KING.
